UNITED STATES PATENT OFFICE

GEORGE H. DIDINGER, OF PHILADELPHIA, PENNSYLVANIA, ASSIGNOR, BY MESNE ASSIGNMENTS, TO SHERWELL CONTROLS, INC., OF NEW YORK, N. Y., A CORPORATION OF NEW YORK

DISPENSING SYSTEM FOR GASOLINE AND THE LIKE

Application filed August 3, 1928. Serial No. 297,844.

My invention relates to dispensing systems and has particular reference to dispensing systems for gasoline and other inflammable or explosive liquids.

5 The general object of my invention is to provide a system of novel character for dispensing gasoline and other inflammable liquids which may be operated with maximum safety and which may be installed for use at 10 relatively small cost.

A further object of my invention is to provide a novel system for dispensing inflammable or explosive liquids including means located or positioned at the point of 15 discharge of the said system, which means must be controlled or operated by the attendant of the system in order to effect the discharge of the said liquid therefrom.

Another object of my invention is to provide 20 a dispensing system of novel character which comprises a discharge nozzle having a valve therein and mechanism adapted to be controlled by the said valve, the mechanism being so constructed and arranged that 25 the valve must be retained in open position by the operative or attendant in order to effect the discharge of the liquid to be dispensed from the said system.

It also is an object of the present invention 25 to provide a novel system for dispensing gasoline and the like, which includes a storage tank the discharge conduit of which is provided with a valve and mechanism responsive to the actuation of the said valve for controlling the supply of fluid under pressure 30 to the said tank for expelling therefrom the liquid to be dispensed, it being necessary for the attendant or operative to retain the valve in open position in order that the said mechanism may be operative for dispensing the 35 said liquid.

A still further object of my invention is to provide a system of the character indicated 40 which is of novel construction and which embodies a storage tank from which the liquid to be dispensed is adapted to be expelled by conducting a fluid under pressure to the said tank, the supply of the said fluid to the tank and the discharge of the liquid therefrom 45 being controlled by mechanism the operation

of which depends upon the actuation or operation of the discharge valve of the said system by the attendant or operative in charge of the said system.

More specifically it is an object of the present invention to provide a novel system for dispensing liquids, which includes a valve for controlling the supply of water to the gasoline tank, for expelling the gasoline therefrom, an emergency or safety control valve in the discharge pipe or conduit which leads from the said storage tank, and a self-closing valve in the discharge nozzle of the said discharge conduit, the last named valve being provided with and connected to a mechanism for controlling the energizing of electromagnets which are adapted to open the other of the said valves, it being necessary to maintain the said discharge valve in open position in order that the other of said valves 70 also may be retained in open position.

Other objects and advantages of my invention will be pointed out in the following description or will be apparent from such description.

In order to more fully understand the invention reference may be had to the accompanying drawing, in which I have illustrated one form of embodiment thereof, but it will be understood that the invention is susceptible of being embodied in other forms of construction than that shown, and that changes in the details of construction may be made without departing from the invention as defined in the claims.

In the said drawing,—

Fig. 1 represents a view partly in section and partly in elevation of a fragmentary portion of a dispensing system embodying the invention;

Fig. 2 is a view partly in elevation and partly in longitudinal section, taken on the line 2—2 of Fig. 3;

Fig. 3 is a cross sectional view taken on the line 3—3 of Fig. 1; and

Fig. 4 is a diagrammatic view of a system embodying my invention.

In the said drawing the numeral 1 designates a storage tank or receptacle for containing the liquid which it is desired to dis-

pense, such as gasoline. The said tank is provided with a fill pipe 2 having a funnel thereon, as shown, and the said tank ordinarily is placed below the surface of the ground. The gasoline or other liquid may be expelled from the tank in any manner well known in the art, but I prefer to introduce water under pressure into the said tank from a suitable source. For this purpose the conduit 3 is connected to the city water supply and leads to a float tank 4 the said conduit terminating within the tank in a valve controlled by a float, the said float and valve being of known construction. As will be understood, the float and the said valve operate to maintain a substantially constant level in the tank. An outlet conduit 5 which is connected at the bottom of the tank 4 extends downwardly and is connected to the bottom of the storage tank, as shown. When the valve 6 which is mounted in the said conduit is opened and the valve 7 is properly adjusted water under substantially constant head will be supplied to the bottom of the tank, the gasoline being elevated by the said water and forced upwardly in the tank and eventually expelled therefrom. The valve 6 preferably is operated by means of the electromagnet 6a and may be of known construction. The valve 7 also is of known construction and comprises a 3-way valve which, when adjusted to one position, permits the water to be supplied to the storage tank, as described already, and when adjusted to another position permits the water which may be contained in the said storage tank to flow from the said tank and to waste through the pipe 8. The valve 7 may be controlled by an operating member or handle 9 which extends into a convenient position for operating the same. The storage tank is provided with a vertically extending discharge pipe 10 the upper extremity of which is connected to a horizontally extending portion 11 connected to a T-fitting, as shown. The upper end of the said T-fitting has connected thereto a vertically extending pipe or conduit 12 the upper end of which is curved downwardly to form a siphon breaker, in known manner. The lower branch of the said T-fitting is connected to a downwardly extending pipe or conduit 13 which extends horizontally, vertically and horizontally, the last named horizontal portion being connected to the valve 14, the discharge outlet of which is connected to the pipe 15 which leads to the flow meter 16. The valve 14 is identical in construction with the valve 6 being actuated by the electromagnet 14a and the meter 16 may be of any construction known in the art. The meter 16 has connected to the outlet side thereof the conduit 17 which conduit is in turn connected to the T-fitting 18. The right-hand portion or branch of the said T-fitting is connected to a nipple 19 which in turn is

connected to an L-fitting 20, the latter being joined to one end of a flexible hose 21 by means of a coupling 22, as shown. The other end of the said hose terminates in a valve 23 the outlet port of which valve is provided with a nozzle 24 adapted to be inserted into the fill openings which ordinarily are provided in the gasoline storage tanks of motor vehicles. The valve 23 is connected to the said hose by means of a nipple 25.

As will be obvious, the valve 23 is adapted to control the flow of liquid through and from the hose, and comprises a valve head 26 which is retained on its seat 27 by means of a spring 28 which engages one side of the said valve. The valve may be operated to open position by depressing the lever 29 the said lever being adapted to engage the plunger 30 which is connected to the said valve and which extends through a packing gland formed in the wall of the valve casing. The inner side of the valve is provided with a stem 31 and a central elongated opening is formed therein which opening extends through the said stem, the valve, and a portion of the stem or plunger 30, the said opening being of proper size to receive one end of a Bowden wire 32 which is retained therein by means of a set screw 32a provided in the discharge side of the valve head. One end of the casing 33 for the said Bowden wire is supported in the nipple 25 by the spider 34 formed on the interior thereof, the said casing being secured in an opening formed in the said spider by a set screw, as shown.

The Bowden wire and the casing therefor extend through the flexible hose or conduit, the fittings which connect the said hose to the T-fitting 18, and through the said T-fitting, as shown in Fig. 2. The spider 35 which is provided on the interior of the lefthand branch of the said T-fitting is adapted to support the end of the Bowden wire casing in which the said wire reciprocates, the said casing being secured in an opening formed in the spider by means of a set screw. The adjacent end of the Bowden wire is secured to the arm 36 rigidly secured to the shaft 37 rotatably mounted in the casing 38, the said casing being mounted on and supported by the said T-fitting.

The shaft 37 extends through a packing gland 39 formed in the wall of the casing 38 and the outer end thereof is provided with a slotted arm 40 rigidly secured to the said shaft and adapted to be oscillated within the casing 41 formed on the casing 38. A bracket 42 which is secured to the inner top side of the casing 41 is adapted to support a tubular receptacle or container 43 which is pivoted to the said bracket by means of a band or support 44 around the center thereof. The said band or support has formed thereon a projection 45 which extends through

the slot of the arm 40, so that movement of the latter causes corresponding movement or oscillation of the said container. The container or receptacle is adapted to be partially filled with an electric current conducting medium, such as mercury, so that when the said container is oscillated clockwise, for example, the mercury will be caused to flow to the lower or righthand end thereof, causing an electric circuit to be completed through the wires 46 and 47 by contacting with the exposed ends of the said wires which extend into the said container through the end wall thereof. The said wires are of flexible character and do not interfere with the oscillation or rocking movement of the said receptacle, only a very slight force being necessary to actuate the said receptacle and to complete the circuit through the said wires. The wires 46 and 47 are connected to the casing 41 through contacts 48 which are insulated from the casing in known manner. The wire 46 is connected to a conductor 49 to which current is conducted from a conductor 50 connected to a suitable source of electric current through the double pole switch 51 when the latter is in closed position. The wire 47 is connected to one end of a conductor 52 which is connected in series with the coil of the electromagnet 14a, conductor 53, the coil of the electromagnet 6a, the conductor 54, the other pole or blade of switch 51, and conductor 55, the current being adapted to flow through the said wire 47 and each of the said electromagnets, through the blade or contact of the double pole switch to the conductor 55, which is connected to the negative side of the current source.

The operation of my novel dispensing system is as follows: When it is desired to dispense gasoline or other liquid the same is introduced into the storage tank or receptacle 1 and the discharge nozzle of the hose is inserted in the fill opening of the receptacle 43 which it is or may be desired to fill with the said gasoline or other liquid. Upon depressing the lever 29 the valve 26 will be depressed whereby a thrust will be imparted to the Bowden wire 32 and the motion of the said valve transmitted thereby to the arm 40, thereby causing the latter to oscillate the receptacle 43 to complete the electric circuit through the wires 46 and 47. The current thereupon flows from the conductor 50 through switch 51 (which is closed), conductor 49, wires 46 and 47, conductor 52, the electromagnets 14a and 6a of the valves 14 and 6, through the other pole of the switch 51 to the conductor 55, thence to the negative side of the current source. As soon as the valve 26 is moved to open position, water, under substantially constant head, will be permitted to flow through the conduit 5, the valve 6, and into the bottom of the storage tank 1, causing the gasoline or other liquid which may

be contained therein to flow through the conduits 10, 11, and 13, through the valve 14, the latter having been caused to open by the electromagnet 14a connected thereto, through the conduit 15, meter 16, conduit 17, and thence through the hose and the discharge nozzle formed thereon.

When the valve 26 is permitted to close, the reverse operation will take place, as will be understood, that is, the flow of current through the electromagnets will be interrupted by the return of the container 43 to normal horizontal position, and the valves 6 and 14 therefore will close. As a result, it will be impossible to effect delivery of liquid from the storage tank 1 until or unless the valve 26 is retained in open position by the attendant or operative, thereby greatly reducing the danger of fire.

Although I have illustrated my invention as being applied to the type of dispensing system wherein water is employed for expelling the liquid from the storage tank, it will be understood that the principle of the invention also is applicable to a system wherein a pump driven by an electric motor is employed for pumping the gasoline from a storage tank therefor. For example, the mercury switch may be employed for controlling the flow of electric current to the motor for driving the pump, in which case the electromagnet 6a and the valve 6 controlled thereby are not used.

It now will be apparent that I have provided a novel system of dispensing liquids of inflammable or explosive character, such as gasoline, which is safe and which may be installed economically for use.

It also will be seen that, by providing a control valve in the discharge nozzle of the hose of a dispensing system, the tanks of motor vehicles and the like may be filled to their capacity without the danger of wasting the gasoline or other liquid, thereby increasing the sale of the said gasoline or liquid. By permitting the supply of water or motive fluid to the storage tank, and the flow of gasoline or other liquid through the discharge conduits of the system, only when the discharge valve is held in open position by the attendant, a novel system is obtained which is safer and which may be operated more economically than those which have been devised heretofore.

Having thus described my invention, what I claim and desire to secure by Letters Patent is:

1. In a system for dispensing liquids, the combination of a storage tank for the liquid to be dispensed, a discharge conduit connected to said tank, said conduit terminating in a flexible hose having a valve in the nozzle thereof, means connected to said valve for controlling the flow of current through an electric circuit, and valve means responsive

to the flow of current through said circuit for effecting the discharge of liquid from said tank.

2. In a system for dispensing liquids, the combination of a storage tank for the liquid to be dispensed, a discharge conduit connected to said tank said conduit terminating in a nozzle having a valve therein, a valve located in said conduit for controlling the flow of fluid therethrough, means connected to said first named valve for controlling the flow of current through an electric circuit, and means responsive to the flow of current through said circuit for effecting the discharge of liquid from said tank and for actuating the said second named valve.

3. In a system for dispensing liquids, the combination of a storage tank for the liquid to be dispensed, a discharge conduit leading from said tank and terminating in a flexible hose, a valve in the nozzle of said hose for controlling the flow of liquid therethrough, an electric circuit having a switch therein for controlling the flow of current through the said circuit, motion transmitting means connected between said valve and the said switch and extending through said hose, means for effecting the discharge of the liquid from said tank into the said conduit and through the said nozzle, and electromagnetic means responsive to the flow of current through said circuit for controlling the said last named means upon actuation of the said first named valve.

35 4. In a system for dispensing liquids, the combination of a storage tank for the liquid to be dispensed, a discharge conduit leading from said tank and terminating in a nozzle, a valve in said nozzle, means for supplying a fluid under pressure for effecting the discharge of the liquid from said tank into and through the said conduit and the said nozzle, a valve in said conduit, an electric circuit having a switch in circuit therewith, means interposed between said first named valve and the said switch whereby movement of the former causes the latter to be opened and closed, and means controlled by the flow of current through the said circuit for controlling said first named means and for opening and closing the said second named valve.

5. In a system for dispensing liquids, the combination of a storage tank for the liquid to be dispensed, a discharge pipe leading from said tank having a flexible conduit connected thereto, said conduit terminating in a nozzle having a valve therein, means for controlling the flow of liquid through said conduit, a valve for controlling the supply of fluid under pressure to said storage tank for controlling the discharge of liquid therefrom, an electric circuit having a switch in circuit therewith for controlling the flow of current through the said circuit, motion transmitting means connected to said first named valve

and extending through the said flexible conduit whereby actuation of the said valve causes the said switch to be actuated, and electromagnets adapted to be energized by the flow of current through the said circuit for controlling said first named means and the said second named valve upon movement of the said first named valve to open position.

6. In a system for dispensing liquids, the combination of a storage tank for the liquid to be dispensed, a discharge pipe leading from said tank having a flexible conduit connected thereto, said conduit terminating in a nozzle having a valve therein, a Bowden wire connected to said valve and extending through said flexible conduit, a conduit for supplying water at substantially constant pressure through the bottom of the said storage tank, a valve in said conduit, a valve in said discharge pipe for controlling the flow of liquid therethrough, an electric circuit, a switch adapted to control the flow of current through said circuit, said Bowden wire being connected to the said switch for actuating the same, and electromagnets in circuit with said circuit for actuating said second and third named valves, movement of the first named valve to open position causing said electromagnets to be energized to open the said second and third named valves.

7. In a system for dispensing gasoline, the combination of a storage tank, a discharge pipe leading from said tank and having a flexible hose connected thereto, said hose terminating in a nozzle having a valve therein, a valve in said conduit for controlling the flow of gasoline therethrough, an electro-magnet for actuating said last named valve, a switch for controlling the flow of current through said electro-magnet, and a Bowden wire interposed between said first named valve and the said switch and extending through said hose, whereby operation of the said valve causes the said switch to be opened and closed.

8. In a system for dispensing gasoline, a storage tank, a discharge pipe leading therefrom and having a flexible hose connected thereto, which hose terminates in a nozzle having a valve therein, a conduit for supplying water to said storage tank to cause gasoline to be discharged therefrom, a valve for controlling the flow of water through said conduit, an electro-magnet for actuating said valve, a switch for controlling the flow of current through said electro-magnet, and a Bowden wire interposed between said switch and said first named valve and extending through said hose, whereby movements of said first named valve cause said second named valve to be opened and closed.

9. In a system for dispensing liquids, the combination with a source of liquid supply, a discharge conduit connected therewith and terminating in a flexible hose having a nozzle

5 valve and switch means for controlling an electric circuit, of an electric device governed by said circuit for effecting discharge of liquid through the conduit, a flexible wire carried by the hose and connected to operate the switch means by a thrust movement of said wire and means at the nozzle end of the hose for imparting thrust movements to the wire for actuating the switch means.

10 10. In a system for dispensing liquids, the combination with a source of liquid supply, a discharge conduit connected therewith and terminating in a flexible hose having a nozzle valve and switch means for controlling an electric circuit, of an electric device governed by said circuit for effecting discharge of liquid through the conduit, a flexible wire carried by the hose and connected to operate the switch means by a thrust movement of said wire and means for conjointly operating the nozzle valve and thrusting said wire.

15 11. In a system of dispensing liquids, the combination of a liquid conduit terminating in a flexible hose, a Bowden wire carried by said hose and comprising a flexible casing and a wire sliding therethrough, operating means carried by the hose for imparting thrust movements to the wire in the casing and liquid flow governing means associated 20 with the conduit and operable upon thrust movements of the wire in the casing.

25 12. In a system of the character disclosed, the combination of a flexible hose, a Bowden wire carried by said hose and comprising a flexible casing and a flexible wire therein and one slidable with respect to the other in various flexed conditions of the hose and Bowden wire, operating means carried by the hose for imparting thrust movements to one 30 of the said members of the Bowden wire and liquid flow governing means associated with the hose and operable upon such thrust movements of said Bowden wire member.

35 13. In a system of the character disclosed, the combination of a flexible hose, a Bowden wire carried by said hose and comprising a flexible casing and a flexible wire therein and one slidable with respect to the other in various flexed conditions of the hose and Bowden wire, operating means carried by the hose for imparting thrust movements to one of the said members of the Bowden wire and liquid flow governing means associated with the hose and operable upon such thrust movements of said Bowden wire member, said Bowden wire being located within the hose and means associated with opposite end portions of the hose for supporting the Bowden wire in freely operating position within the 40 hose.

45 14. In a system for dispensing liquids, the combination of a liquid conduit terminating in a flexible hose, a flexible mechanical connection carried by said hose and comprising a thrust transmitting member flexible with

the hose, operating means carried by the hose for imparting thrust movements to said thrust transmitting member and liquid flow governing means associated with the conduit and operable upon said thrust movement 70 of the thrust transmitting member.

15 15. In a system for dispensing liquids, the combination of a liquid conduit terminating in a flexible hose, a flexible casing carried by said hose, a thrust transmitting medium 75 guided in and flexible with said casing, means at the discharge end of said hose for initiating and imparting thrust movements to said thrust transmitting medium in the flexible casing, mechanism actuated by the thrust movements of said medium and liquid flow governing means controlled by said mechanism.

16 16. In a system for dispensing liquids, the combination of a source of liquid supply, a discharge conduit connected therewith and terminating in a flexible hose having a nozzle valve, a flexible casing carried by said hose, a thrust transmitting medium operating in said flexible casing, liquid flow governing means associated with the conduit and operable upon thrust movements of said thrust transmitting medium and means for conjointly operating the nozzle valve and effecting thrust action of the thrust transmitting 85 medium.

20 17. In a system for dispensing liquids, the combination of a liquid conduit terminating in a flexible hose having a nozzle valve, liquid flow governing means associated with the conduit, a flexible wire carried by the hose and connected to operate the liquid flow governing means by a thrust movement of said wire, means for conjointly operating the nozzle valve and thrusting said wire and adjustable securing means for the end portion of said thrust wire.

25 18. In combination with a flexible hose having a spring seated nozzle valve and a handle for thrusting said nozzle valve open 100 against the force of the closing spring, a flexible thrust wire connected with said valve and actuated thereby and liquid flow governing means associated with the hose and shifted in one direction on the thrust movement of the wire and in the return direction on the closing of the nozzle valve by the valve closing spring.

30 19. In combination with a flexible hose having a spring seated nozzle valve and a handle for thrusting said nozzle valve open against the force of the closing spring, a flexible thrust wire connected with said valve and actuated thereby and liquid flow governing means associated with the hose and shifted in one direction on the thrust movement of the wire and in the return direction on the closing of the nozzle valve by the valve closing spring, said thrust wire being located 115 within the hose and the valve having a stem 120

portion, the thrust wire being connected with said stem portion of the valve.

20. In combination with a flexible hose having a spring seated nozzle valve and a handle for thrusting said nozzle valve open against the force of the closing spring, a flexible thrust wire connected with said valve and actuated thereby and liquid flow governing means associated with the hose and shifted in one direction on the thrust movement 10 of the wire and in the return direction on the closing of the nozzle valve by the valve closing spring, said nozzle valve having a stem portion and screw means for fastening the thrust wire to said stem portion of the nozzle valve.

21. In a system of the character disclosed, the combination of a liquid conduit terminating in a flexible hose having a nozzle, a flexible power transmission connection guided 20 within the hose, means at the nozzle end of the hose for actuating said flexible power transmission connection, the liquid conduit at the opposite end of the hose having a casing for said flexible power transmission connection and said flexible power transmission connection extending into said casing, an electric switch located outside the casing and means extending in liquid tight operating 25 relation from that portion of the flexible power transmission connection within the casing to the switch without the casing.

22. In a system of the character disclosed, the combination of a liquid conduit terminating in a flexible hose having a nozzle, a flexible power transmission connection guided 35 within the hose, means at the nozzle end of the hose for actuating said flexible power transmission connection, the liquid conduit at the opposite end of the hose having a casing for said flexible power transmission connection, an electric switch located outside the casing and means extending in liquid tight 40 operating relation from that portion of the flexible power transmission connection within the casing to the switch without the casing, said flexible power transmission connection including a flexible casing and a flexible thrust wire operating therein and means for supporting the opposite end portions of said 45 flexible casing in the nozzle portion of the hose and in the casing aforesaid of the liquid conduit.

23. In apparatus of the character disclosed, 50 the combination of a flexible hose having a nozzle and a spring seated valve, handle means on the nozzle for thrusting the valve open in opposition to the valve closing spring, flexible power transmission means within the 55 hose including a flexible casing and a thrust wire operating therein, the valve having a stem portion and the thrust wire being attached to the same, a spider supporting the flexible casing in alignment with said stem 60 portion of the valve, an electric switch and

operating connections from the opposite end of the thrust wire to said electric switch.

24. In liquid dispensing apparatus, a conduit, an electric switch and a liquid control valve associated with said conduit and disposed in relatively spaced relation, a motion transmitting device connecting said spaced switch and valve and including a thrust transmitting mechanical connection and a guide in which the same reciprocates, the 70 switch being connected to be actuated by the thrust movements of said thrust transmitting mechanical connection and means for effecting conjoint switch-actuating thrust operation of said thrust transmitting connection 75 and opening movement of the valve.

25. In a system for dispensing liquids, the combination of a liquid conduit terminating in a flexible hose provided with a nozzle valve, a flexible casing carried by said hose, a thrust transmitting medium guided in and flexible 80 with said casing, liquid flow governing means associated with the hose, means actuated by the thrust movements of said thrust transmitting medium for controlling said liquid flow 85 governing means and a handle for the nozzle valve and for imparting thrust transmitting movements to said thrust transmitting medium in the flexible casing.

26. In a system of the character disclosed, 90 the combination of a liquid conduit terminating in a flexible hose having a nozzle valve, a flexible power transmission connection carried by said hose and flexible therewith, liquid flow governing means associated with the 95 opposite end of the hose, handle means for conjointly operating said nozzle valve and said flexible power transmission connection and means for variably connecting the flexible power transmission connection with said 100 flow governing means for regulating operation of said flow governing means in conjunction with the nozzle valve operation.

27. In a system of the character disclosed, 105 the combination of a liquid conduit terminating in a flexible hose having a nozzle valve, a flexible power transmission connection carried by said hose and flexible therewith, liquid flow governing means associated with the opposite end of the hose, handle means for conjointly operating said nozzle valve and said flexible power transmission connection, said flexible power transmission connection being arranged to actuate said flow governing 110 means and variable securing means at one end of said flexible power transmission connection including a movable member having an opening slidably receiving one end of the power transmission connection and an adjustable device for variably gripping said 115 slidably received portion of the power transmission connection for regulating the conjoint operation of nozzle valve and flow governing means.

28. In apparatus of the character disclosed, 120

the combination of a flexible hose, liquid flow governing means associated therewith, flexible motion transmitting means extending through the hose and flexible therewith,
5 means adjacent one end of the hose for relatively centering and supporting one end of the flexible motion transmitting means in the hose and in operating relation with the liquid flow governing means, centering means
10 for supporting the opposite end portion of said flexible motion transmitting means in generally centered position in the hose and hand operated mechanism associated with said latter centered end portion of the motion
15 transmitting means for actuating said flexible motion transmitting means to effect operation of the flow governing means.

In testimony that I claim the foregoing
20 as my invention I have hereunto signed my
name this 26th day of July, A. D. 1928.

GEORGE H. DIDINGER.
